UNITED STATES PATENT OFFICE.

JOHN J. CARMODY, OF MOUNT VERNON, NEW YORK.

BUTTON.

No. 918,960.

Specification of Letters Patent.

Patented April 20, 1909.

Application filed February 18, 1908. Serial No. 416,495.

To all whom it may concern:

Be it known that I, JOHN J. CARMODY, a citizen of the United States, residing at Mount Vernon, in the county of Westchester 5 and State of New York, have invented new and useful Improvements in Buttons, of which the following is a specification.

This invention relates to buttons and more particularly to detachable buttons such as are used on shirts and other garments and its object is to provide attaching means to prevent the release and loss of the button from its hole. This attaching means being a part of the button itself and stamped from 10 the metal forming the button as will be more fully explained and described in the following specification, set forth in the claim and illustrated in the drawings where:

Figure 1 is a perspective view of the improved button. Fig. 2 is a plan view of same. Fig. 3 is a side elevation.

This improved button is of the ordinary shape and appearance with a head 5 at the outer end of the stem 6 which is carried by a 25 base 7. The base is of thin metal and the stem being a separate piece is welded or soldered thereto and is adapted to fit within the inner surface of the garment while the head and stem protrude through the button 30 hole.

Cut from the sheet metal base are tongues 8 whose ends are raised a suitable distance above the surface of the base and remain parallel with it. This arrangement of the 35 tongues is effected by turning them backward and upward as at 9 after being cut or stamped and then forward into the horizontal position.

In putting this button into position the head and shank are passed through the button hole and then the tongues are also passed through the hole and given a turn so as to bring them across the button hole at right angles offering an obstruction to the return of the shank and head after being passed 40 through the hole and thereby not only preventing its loss but securing the button more rigidly for use. When the button is thus located the distance between the two points 45 9 causes a slight spread of the button hole and the thickness of the fabric or other material fits closely in the two depressions at that point in consequence of the separation of the 50 two sides of the button hole.

It is obvious that the tongues may be cut 55 from the base on different lines or bent to otherwise engage the button hole without departing from the essential features shown.

What I claim as new and desire to secure 60 by Letters Patent is:

A button comprising a base, a shank, and a head, said base having integral tongues struck up therefrom on opposite sides of and disposed radially with reference to the shank, said tongues having their terminal portions 65 spaced from and substantially parallel with the inner face of the base whereby to coat with the base in engaging material about the button hole.

In testimony whereof, I affix my signature 70 in presence of two witnesses.

JOHN J. CARMODY.
